J. A. Rollins,
Melodeons,
No 15,019, Patented June 3, 1850.

UNITED STATES PATENT OFFICE.

JOSIAH A. ROLLINS, OF BUFFALO, NEW YORK.

MELODEON.

Specification forming part of Letters Patent No. 15,019, dated June 3, 1856; Reissued August 7, 1866, No. 2,330.

To all whom it may concern:

Be it known that I, JOSIAH A. ROLLINS, of Buffalo, in the county of Erie and State of New York, have invented certain new 5 and useful Improvements in Melodeons; and I do hereby declare that the following is a full, clear, and exact description of the same, reference being had to the accompanying drawings, forming a part of this 10 specification, in which—

Figure 1, is a transverse vertical sectional view of all the principal operating parts of a melodeon with my improvements. Fig. 2, is a transverse section of the tube board. 15 Fig. 3, is a plan of the tube board.

Similar letters of reference indicate corresponding parts in the several figures.

The object of this invention is, so to arrange within the instrument, four sets of 20 reeds and to combine two sets of valves, to be played by one set of keys, as to keep all the reeds on one tube board and to make the construction of the instrument simpler, than when the reeds are arranged in two banks, 25 and at the same time to avoid making the depth or width of the case of the four-reed instrument any greater than that of an instrument of the common kind, having only one set of valves.

30 To enable others skilled in the art to make and use my invention I will proceed to describe its construction and operation.

A, is the bellows.

B, is the wind receiver.

35 C is the stationary frame to which the sides of the wind receiver are attached and which serves to support the tube board D.

The above parts are all the same as in a common melodeon having only one set of 40 valves, with the exception that cavities a, a, are formed in the front and back of the upper side of the frame, by which means the upper part of the wind receiver is widened on each side to the extent indicated 45 between the lines b and c, in Figs. 2 and 3, without enlarging the frame C, the tube board or the case, by simply extending it between the frame C, and the tube board, instead of limiting its width by the interior 50 of the frame, as indicated between the lines b, b, according to the usual plan. In this way a sufficient width is obtained for two sets of valves E and E', to work under the tube boards to admit wind to two double 55 sets of reeds e, e, and e', e', arranged above

them. The valves E of the front set are hinged at their front extremities and the valves E' of the back set are hinged at their rear extremities. This arrangement brings the movable ends of the valves together and 60 the end of every valve E, of the front set overlaps the end of a corresponding valve E', of the back set, as shown in Fig. 1, one guide pin f, serving for the two valves. This mode of fitting every two corresponding 65 valves of the two sets enables the valves to be opened by a single acting key E, operating like that which is employed to open a single valve, by a push down pin g, pressing on the front valve the back valve being 70 opened by the front one overlapping it and pressing it down, whenever it is itself depressed by the key. Both sets of valves are furnished with springs h, h, of the usual kind. The rear valves E', are attached to 75 the tube board by a simple hinge i, of leather, but the front valves E, in addition to their being attached by a strip of leather j, are supported by a fixed strip of wood k, see Fig. 1, which extends from end to end 80 of the whole set of valves and serves as a kind of shelf for their ends to rest upon. This strip is necessary for the support of the front valves, as when they are depressed by the push down pins, the whole of the re- 85 sistance of the springs of the corresponding rear valves is transmitted so as to act in a downward direction on the hinges of the front valves and the leather hinge alone would be insufficient to bear it. The pres- 90 sure on the hinges of the rear valves is in an upward direction like that on the valves of other melodeons and is sustained by the tube boards, therefore no support underneath them is necessary. 95

What I claim as my invention and desire to secure by Letters Patent, is,

1. The extension of the wind receiver toward the back and front of the case by forming cavities a, a, between the frame C, 100 and the tube board D, substantially as herein described thereby obtaining room under the tube board for the operation of two sets of valves, one behind the other to operate on four sets of reeds without increasing the 105 usual size of the case.

2. The arrangement of the two sets of valves E and E', to bring their movable ends together and the fitting of the said ends together so that by the depression of 110

the valves of one set, to open them, the corresponding valves of the other set are depressed and opened, thereby effecting the opening of the two sets of valves by a single set of push-down pins, and keys of ordinary construction.

3. Supporting the front set of valves at

their hinges by a strip K, of wood or other material substantially as and for the purpose set forth.

JOSIAH A. ROLLINS.
